P. W. WASCHAU,
INDICATOR FOR DOORS,
APPLICATION FILED APR. 12, 1915.

1,171,287.

Patented Feb. 8, 1916.

UNITED STATES PATENT OFFICE.

PAUL W. WASCHAU, OF MAYWOOD, ILLINOIS.

INDICATOR FOR DOORS.

1,171,287.

Specification of Letters Patent.

Patented Feb. 8, 1916.

Application filed April 12, 1915. Serial No. 20,907.

To all whom it may concern:

Be it known that I, PAUL W. WASCHAU, a citizen of the United States, and a resident of the town of Maywood, county of Cook, and State of Illinois, have invented certain new and useful Improvements in Indicators for Doors, of which the following is a specification.

My invention relates to improvements in an indicating device for doors, and has for its object the production of an indicator of this character especially designed for use in connection with hotels for indicating to employees or others, whether or not a particular room is occupied, without the necessity of opening the door such as is required at the present time.

A further object is the production of a device as mentioned which will be of simple construction and efficient in use.

Other objects will appear hereinafter.

The invention consists in the combinations and arrangements of parts hereinafter described and claimed.

The invention will be best understood by reference to the accompanying drawing forming a part of this specification, and in which,

Figure 1 is a fragmentary front elevation of a door equipped with an indicator embodying the invention, Fig. 2 is an enlarged section taken on line $x-x$ of Fig. 1, Fig. 3 is an enlarged sectional view of the door and door casing exposing the indicating device, one side of the housing of the latter being broken away to expose underlying parts, Fig. 4 is an enlarged section taken on line $y-y$ of Fig. 1, and Fig. 5 is a detail end view of the operating handle of the indicator.

The preferred form of construction, as illustrated in the drawing, comprises a substantially rectangular housing 1 mortised in the free edge of the door in connection with which the indicator is employed, at a height which will be convenient for readily observing the same. The housing 1 is secured in position by means of screws 3. Slidably mounted within the housing is a plate 4 upon one side of which are provided indications "In" and "Out" adapted for exposure at exposure opening 5 formed in one side of housing 1. The opening 5 registers with a corresponding opening 6 which is formed in the outer side of the door 2, a finishing plate 7 surrounding the opening 6,

as shown. The arrangement is such, as will be seen, that when the plate 4 is at one terminal of movement, the word "In" will be exposed, and when said plate is at its other terminal of movement the word "Out" will be exposed. Said plate 4 is carried by a rack bar 8 which is shiftably mounted in housing 1, guide lugs 9 and 9' being formed upon one wall of said housing for engagement with the upper and lower edges of said rack bar, as clearly shown in Fig. 3. Formed in the outer end of the housing 1 is a slot 10 through which the outer end of said rack bar is adapted to project when the plate 4 is in a position with the word "In" thereof exposed. The outer end of said rack bar, when in the latter position, is adapted to engage with a slot 11 provided for the reception thereof in the adjacent side of the door casing 11' to serve as a means of locking the door in closed position. When the plate 4 is shifted to its other terminal of movement, or to a position in which the word "Out" is exposed, the outer end of rack bar 8 will be retracted out of engagement with the slot 11 or to inoperative position.

The rack bar 8 is actuated by means of a segmental pinion 12 rotatably mounted in the housing 1, said pinion meshing with rack teeth 13 formed upon the inner end of bar 8. The pinion 12 is manually rotated through the medium of a handle or thumb-turn 14 having a stem 15 provided at its inner end with a square socket 16 adapted for snug engagement with an axial lug 17 of corresponding formation provided upon the adjacent side of pinion 12. The handle 14 is secured to said pinion by means of a screw 18 projecting through said handle and the stem thereof and engaging in the adjacent side of said pinion, as shown. A bushing 19 is provided in the door for engagement with the handle stem 15. With this arrangement then, it will be seen, that shifting of the rack bar 8 to move the indicator plate 4 is effected by turning of the handle 14, the arrangement being such that, when said handle is in vertical position, as shown, the rack bar will be at its outer terminal of movement and the word "In" exposed, and when said handle is in horizontal position, said rack bar will be at its inner terminal of movement and the word "Out" exposed. With this arrangement, it will be seen that, in use when a room is occupied, in order

to advise those upon the outside or in the corridor of this fact, it is only necessary to turn the handle 14 to the position shown in the drawing, in which event the word 5 "In", exposed at the outer side of the door, will advise that the room is occupied. Upon the occupant leaving the room, he will be required to turn the handle 14 to withdraw the outer end of bar 8, in which event the 10 word "Out" will be exposed at the outer side of the door, to advise of this fact. By so arranging the bar 8 that the outer end thereof projects into locking position upon the device being adjusted to indicate the 15 occupancy of the room, provision is made whereby it will be impossible for the occupant to neglect adjusting the device to indicate his departure or vacation of the room, upon leaving, since it will be impossible to 20 open the door without first adjusting the device to expose the word "Out". The pinion 12 is formed with a reduced portion 20 which serves as a stop for the plate 4 in the movement of the latter to a position in which 25 the word "Out" is exposed.

The device is simple and economical in construction and hence may be manufactured at a low cost, and the construction permits of ready installation in any door.

30 When a hotel door is equipped with this device, it will avoid the annoying and exceedingly distasteful disturbance of a slumberer occupying a room by hotel employees, such as chamber maids, who at the present 35 time are required to enter a room in order to determine whether or not the same is occupied.

While I have illustrated and described the preferred form of construction for carrying 40 my invention into effect, this is capable of variation and modification without departing from the spirit of the invention. I,

therefore, do not wish to be limited to the precise details of construction set forth, but desire to avail myself of such variations 45 and modifications as come within the scope of the appended claims.

Having described my invention what I claim as new and desire to secure by Letters Patent is:

50 1. An indicator for doors comprising a housing having an exposure opening in one side thereof; a shiftably mounted member arranged in said housing having indications thereon adapted for exposure at said exposure opening; means for shifting said member, said means comprising a rack bar connected with said member; a manually operable pinion meshing with said rack bar; and means on said pinion for engagement 55 with said member to limit shifting movement thereof in one direction, substantially as described.

2. An indicator for doors comprising a housing having an exposure opening in one 60 side thereof; a shiftably mounted member arranged in said housing having indications thereon adapted for exposure at said exposure opening; means for shifting said member, said means comprising a rack bar 65 connected with said member; a manually operable pinion meshing with said rack bar; and an annular shoulder on said pinion for engagement with said member to limit shifting 70 movement thereof in one direction, substantially as described.

75 In testimony whereof I have signed my name to this specification in the presence of two subscribing witnesses.

PAUL W. WASCHAU.

Witnesses:

JOSHUA R. H. POTTS,
ARTHUR A. OLSON.
